Primary Examiner — Vy N Koenig(74) *Attorney, Agent, or Firm* — Warner Norcross + Judd LLP(57) **CLAIM**

The ornamental design for an emergency cot side rail, as shown and described.

DESCRIPTION

FIG. 1 is a back (inner side) elevation view of a left side emergency cot side rail showing our new design;
 FIG. 2 is a front (outer side) elevation view thereof;
 FIG. 3 is a perspective view of the back (inner side) thereof;
 FIG. 4 is a bottom plan view thereof;
 FIG. 5 is a top plan view thereof;
 FIG. 6 is an end elevation view thereof; and,
 FIG. 7 is a second end view thereof.

The broken lines are included for the purpose of illustrating portions of the emergency cot side rail that form no part of the claimed design.
